United States Patent Office.

THOMAS SCHOENBERGER BLAIR, OF PITTSBURG, PENNSYLVANIA.

Letters Patent No. 97,754, dated December 14, 1869.

IMPROVED MODE OF TREATING CONGLOMERATES OF CAST-IRON.

The Schedule referred to in these Letters Patent and making part of the same.

To all whom it may concern:

Be it known that I, THOMAS SCHOENBERGER BLAIR, of the city of Pittsburgh, in the county of Allegheny, and State of Pennsylvania, have invented an Improved Treatment of Conglomerates of Cast-Iron, and other substances; and I do hereby declare that the following is a full and exact description of the said invention, reference being had to the accompanying drawing, and to the figures and letters marked thereon; that is to say—

This invention relates to the treatment of "pig-bloom," however produced, whether with oxides alone, as a mixture, or with carbonaceous matter alone, or both combined, or with any other substance employed as a chemical agent therewith.

I have found that such conglomerates, or "pig-blooms," as they are termed, are, for reasons herein-after explained, difficult of management, under the methods of treatment hitherto employed for converting them into wrought-iron; and

The object of my present invention is to obviate these difficulties by an operation intermediate between the production of the pig-bloom and its introduction into the reverberatory furnace for conversion.

The difficulties referred to may be described as follows:

First, if the pig-blooms be charged into the furnace unbroken, a considerable amount of labor will be required to break them up in time to obtain an equal exposure of all the parts to heat.

Second, if the pig-blooms are allowed to remain unbroken, the cellular or spongy character of the mass renders it a bad conductor of heat, and a wasteful amount of time is required to bring the interior of each bloom "to nature."

Third, if the conglomerate be made in the shape of "pig-scrap," or if the pig-blooms be broken up into scrap, and the charge be put into the reverberatory furnace cold, the furnace-bottom is chilled to such an extent that it does not recover its proper temperature during the working of the charge, to the great disadvantage of the operation. In addition to this, the workman is obliged to bestow a large amount of labor on it to keep the colder portion continually turned up from beneath.

In each of the above methods, the chemical operations are, with proper care and skill, successfully carried out, and the conglomerate converted into good wrought-iron.

The difficulties involved in the treatment are entirely mechanical, and the purpose of the present invention is to supply a mechanical remedy therefor.

My improved process is founded on the fact, ascer-

tained by experiment, that the pig-bloom is very friable when first raised to a red heat; and

My invention consists in first raising the pig-bloom to such a heat as will render it friable, and, while in that state, reducing it to small fragments, and introducing it at once, before it has time to cool, into the reverberatory furnace.

For this purpose, I employ a heating-furnace, so constructed as to impart the requisite heat to the pig-blooms, from which furnace they are drawn consecutively, and subjected to the action of a crushing-apparatus, which instantly reduces them to scrap, which again, with the least possible loss of heat, is charged into the reverberatory furnace.

By this method, the workman receives a charge ready delivered into his furnace, requiring no breaking up, and very little turning over, and which cools the furnace-bottom so slightly as not to retard seriously the working of the charge.

It will be obvious to all skilled in the art, that a great variety of forms and arrangements of furnaces, and apparatus for the heating, crushing, and delivery of the conglomerate, may be employed, and it is a great advantage that these admit of many modifications, as it is thereby rendered easy to adapt the above process to the limitations of space, and the requirements of works already constructed.

I do not claim, therefore, any special construction or arrangement of furnaces and apparatus for the purposes of my invention, but simply the combined process before described.

In the arrangement of apparatus, I prefer to employ a heating-furnace or muffle, so constructed that the blooms are charged in at one side and withdrawn from the other.

The heat is admitted through the floor of the chamber containing the blooms, and these are supported on rails, which leave a space between them and the floor, so that the heat is applied in such a manner as to require no turning over of the blooms. They thus require no handling beyond the charging and drawing.

In front of the drawing-side of the heating-chamber is set a crushing-machine, (which may consist either of one or more pairs of rolls, or of a "stone-crusher," or of any similar suitable machine of known construction,) so placed that the bloom will readily fall into it when drawn from the chamber, and that the resulting crushed material or scrap shall fall directly into a wagon or car, which shall convey the charge thence to any suitable reverberatory furnace of known construction.

The apparatus which I propose to use needs no particular description, and needs not to be such, ex-

actly, as I have described, as any mode of or apparatus for heating the pig-bloom, and reducing it, while hot, to small fragments, may be employed which will most conveniently and effectually accomplish the purpose.

Having thus described the nature of my invention, and in what manner the same is to be performed,

What I claim, and desire to secure by Letters Patent, is—

The before-described improved treatment of pig-bloom, wherein the pig-bloom is first heated to the

requisite degree to render it friable, is then crushed, and the crushed material charged at once into a reverberatory furnace, with the least possible loss of heat.

In testimony whereof, I have signed my name to this specification, in the presence of two subscribing witnesses, this 10th day of August, 1869.

THO. S. BLAIR.

Witnesses:

CHAS. D. ABEL,
A. W. TAYLOR.
